 L. K. Löhm.

UNITED STATES PATENT OFFICE.

EMIL T. NEBEN, OF RIDGEWOOD, NEW JERSEY, ASSIGNOR, BY MESNE ASSIGNMENTS,
TO NEBEN MANUFACTURING COMPANY, A CORPORATION OF NEW JERSEY.

MOLD FOR CASTING PERIPHERALLY-CLOSED RELIEF-ENGRAVED PRINTING-CYLINDERS.

1,261,642.

Specification of Letters Patent.

Patented Apr. 2, 1918.

Application filed August 2, 1916. Serial No. 112,642.

To all whom it may concern:

Be it known that I, EMIL T. NEBEN, a citizen of the United States of America, and a resident of Ridgewood, county of Bergen,

5 State of New Jersey, have invented certain new and useful Improvements in Molds for Casting Peripherally-Closed Relief-Engraved Printing-Cylinders, of which the following is a specification.

10 This invention has reference to novel molds for casting peripherally closed, relief engraved printing cylinders to be used in the art of continuous rotary printing.

Heretofore relief engraved printing cylinders could not conveniently and cheaply be produced in any size of tubular form as uninterrupted all closed complete cylinders for continuous rotary printing. An open longitudinal slot was always left in the former cylinders.

20 Such open cylinders were used only for printing single pages where a blank top and bottom space was left or for other printed matter which did not require continuous rotary printing and therefore are very much limited in the production of desirable designs. If a cylinder with a relief engraved surface portion is cast in a tubular casting mold on a core or tube the cooling metal shrinks upon the core

30 so tight that it is impossible to remove it from the casting mold. An outer mold of course may be destroyed or taken off but the inner core of the tubular casting mold can not be removed and the engraved cylinder 35 can not be separated therefrom for the reason that the stereotype metal shrinks upon the inner core when cooling, therefore it is impossible to remove the relief engraved cylinder from the inner core of the casting 40 mold.

A complete copper roll certainly may be engraved by hand or milled in by machinery in intaglio but such process is very limited to certain designs only and prohibitive as 45 to cost for many designs that can not be accomplished by the well known intaglio process.

The present invention has for its purpose to produce uninterrupted, tubular, peripherally closed, relief engraved, printing cylinders which present well recognized advantages but so far could not have been produced by easy and cheap methods. The former cylinders have a free open slot or

space where printing can not be done and 55 therefore such cylinders can not be used for continuous rotary commercial printing in silk works, oil cloth printing shops and wall paper factories for printing in relief from cylinder print rolls.

60 For the purpose of overcoming the described defects and broadening the field for relief printing I have produced a peripherally closed, relief engraved, printing cylinder which can be used for continuous printing upon large or small webs of silk, cotton, oilcloth, wall paper, fancy paper and the like taking in a vast scope of fine commercial and art printing. This is accomplished by casting the design in a complete cylinder 65 from a matrix adjusted in a tubular mold provided inside with an expandable core. For the purpose of being able to remove the mold from the cylinder casting and use it over again the said mold is divided into a plurality of curved sections, say 70 four. Some of the sections are hinged to the adjoining sections and provided with locking devices. The curved sections form a complete tubular mold. Such tubular sections are hinged together and actually form doors which may easily be assembled to form a tubular mold and locked. After the cylinder casting has been made the locks 75 may be released and the doors opened so that the outer mold may be removed from the cast relief engraved printing cylinder. The expanding arbor or core within the cast cylinder is then released and removed.

80 The design is produced in line or half tone engraving on a flat surface from which a common matrix is made such as used for instance as paper matrices employed in making stereotypes. A paper matrix is produced and cut so that the designs or patterns match perfectly when in tubular form, then the paper matrix is curved and placed into the tubular mold with the face toward the inner expanding arbor of the mold.

85 Within the divided mold there is the expandable core or arbor which is placed centrally in the tubular casting mold and is made substantially of the construction described in Letters Patent granted to Wood ass'or Pat. No. 1,056,480, March 18, 1913, 90 for expanding core or arbor. The divided mold is so constructed as to allow molten metal to enter from the bottom upward,

When the matrix has been adjusted in the tubular mold and the expansible core set therein the molten metal is forced up from the bottom until the mold is filled whereby 5 the engraved cylinder in relief is created. The molten metal is introduced from the bottom for the purpose of conveniently expelling the air bubbles and thereby producing a clean and sharp casting free from dirt 10 and air holes.

When the casting has thoroughly cooled off and set the outer mold is removed as hereinbefore described and the expanding core within released by decreasing its 15 diameter from the original size upon which the engraved cylinder was cast. Thus the cast engraved cylinder is free from both the outer mold and the inner expanding core or arbor. The cast cylinder produced 20 in the described manner is not inseparably shrunk on the inner core which is expansible and may be reduced to a small diameter. The cast free cylinder being in an all closed 25 uninterrupted form of relief engraved cylinder is now ready for any rotary printing press.

One of the chief and all important advantages of this novel peripherally closed tubular printing in relief from a cylinder is 30 the great speed in the production of printed goods, and in the saving of time in preparing the printing cylinder in the casting mold. Formerly it required hours to make up a printing form on the press ready to 35 print, by these cylinders it takes but minutes.

In order to render the invention entirely clear reference is had to the accompanying drawing in which:

40 Figure 1 represents in longitudinal central section a mold for producing cast, peripherally closed, relief engraved printing cylinders, showing certain parts in elevation and embodying in desirable form the 45 present improvements.

Fig. 2 illustrates this mold in vertical elevation.

Fig. 3 is a top plan view of the same.

Fig. 4 indicates a cast, peripherally 50 closed, relief engraved printing cylinder.

Similar characters of reference denote like parts in all the figures.

In the drawing *a* represents the outer mold which forms a cylinder having a bottom *b*. The cylindrical mold *a* is composed of four curved sections *a*¹, *a*², *a*³, *a*⁴ as best shown in Fig. 3. These curved sections are united by hinges *c*, *c*¹, *c*² and the sections *a*², *a*³ are provided with locks *d* of any suitable construction. The locks are provided each with a handle *d*¹ and may easily be opened and closed. The bottom *b* of the mold has two openings through which pipes 60 *e* *f* pass. These pipes are connected by a 65 pipe *g* from the center of which a pipe *h*

leads to the vessel containing the molten metal. On the inner surface of the mold a paper matrix *i* is located with the design thereon toward the interior of the mold. The design is properly matched at its joining edges. As herein stated the matrix is made preferably like the paper matrices employed in making stereotypes. 70

Within the mold there is the expanding core or arbor composed of four curved sections *j*, *k*, *l*, *m* with spaces between *j*¹, *k*¹, *l*¹, *m*¹. These four sections or shell pieces, by virtue of the spaces between them may be expanded and contracted. To render this clear the operation of the Wood expanding core may be shortly reviewed. A tube *n* passing through the device has at each end a head *o* and a journal plug *p* fits into each head *o*. An adjusting head *q* is mounted upon the tube *n* and held in position by a collar *r*. The broadened top portion of the adjusting head *q* is provided with a plurality of openings *s* which openings or spanner holes are adapted to receive a spanner wrench whereby the adjusting head *q* may be rotated. The shell pieces are in connection with the adjustable head. If the head is rotated in one direction the shell pieces expand and if rotated in the other direction the shell pieces contract. 85

In order to cover the spaces *j*¹, *k*¹, *l*¹, *m*¹ between the shell pieces of the expansible core a paper tube *t* is slipped onto the shell pieces of the core and the core is then expanded so as to rest tightly against the 100 paper tube. As seen from Fig. 1 of the drawing there is a distance between the paper matrix *i* and the paper tube *t* and the space between the tube and matrix is the space to be filled up by the molten metal to 105 form the cast, peripherally closed, relief engraved printing cylinder. The pipes *e*, *f* through which the molten metal is introduced into the mold are so arranged that they issue right into this space. When the 110 molten metal rising from the bottom up has filled the space between the matrix and the paper tube a cast, peripherally closed, relief engraved printing cylinder *u* is formed. As soon as the cast printing cylinder has cooled 115 off and completely set the locks *d* outside on the mold are released and the sections or doors forming the outer mold opened. Now the mold is taken away and the matrix removed exposing the cast, relief engraved 120 printing cylinder. In order to remove the expanding core the spanner wrench is applied and the core contracted whereupon it may easily be taken out of the cast printing cylinder. The paper tube *t* then is taken 125 out leaving the cast, relief engraved printing cylinder ready to be applied to any rotary printing press.

It is evident that the cast, relief engraved printing cylinder, closed around its entire 130

circumference and produced in one piece can be used for continuous printing without any interruption until a roll or web of silk, cotton, oilcloth, wall paper, fancy paper and 5 the like has passed through the rotary printing press. A new roll or web may then be inserted and the rotary printing continued in the described manner. All parts of the mold are used over and over again and as 10 the design is cast in the complete cylinder from a matrix adjusted in the tubular mold a great variety of cast, all closed rotary printing cylinders may be produced from one mold. A different printing cylinder always results from a different matrix with 15 different designs thereon. Thus one mold of standard size may be used for the production of a great variety of cylinders because the only part used in the mold which changes 20 is the matrix with the designs thereon.

For exceptionally large or small work molds of the same construction are used which are large or small as required whereby large or small cast, relief engraved printing 25 cylinders are produced which are peripherally closed and adapted for continuous rotary printing.

I claim as my invention:—

1. A mold for producing cast, peripherally closed, relief engraved printing cylinders for continuous rotary printing comprising a divided tubular outer mold with a separate bottom and open at the top, an expandable core centrally within the mold, 30 means on the inner surface of said mold adapted to produce a completely closed outer surface, so arranged that a space remains between said means and core, and means for introducing molten metal into said space 35 from the bottom upward.

2. A mold for producing cast, peripherally closed, relief engraved printing cylinders for continuous rotary printing comprising a tubular outer mold composed of a 40 plurality of curved sections hinged together, locks on some of said sections, a separate bottom on said mold, an expandable core centrally within the mold, a tubular matrix on the inner surface of the mold, means on the 45 core when expanded to produce a completely closed outer surface, so arranged that a space remains between said matrix and means, and means for introducing molten metal into said space from the bottom upward.

3. A mold for producing cast, peripherally closed, relief engraved printing cylinders for continuous rotary printing comprising a tubular outer mold composed of a plurality of curved sections, a separate bottom on said mold, an expandable core centrally 50 within the mold, a tubular matrix mounted on the inner surface of the mold, a paper tube on the core when expanded, so arranged that a space remains between said matrix and tube, and means for introducing 55 molten metal into said space from the bottom upward.

4. A mold for producing cast, peripherally closed, relief engraved printing cylinders for continuous rotary printing comprising a tubular outer mold composed of a plurality of curved sections, a separate bottom on said mold, an expandable core centrally 60 within the mold, a tubular matrix mounted on the inner surface of the mold, a paper tube on the core when expanded, so arranged that a space remains between said matrix and tube, and means for introducing 65 molten metal into said space from the bottom upward.

5. A mold for producing cast, peripherally closed, relief engraved printing cylinders of various thickness for continuous rotary printing comprising a removable tubular outer mold, a separate bottom, a variably expandable core centrally within the 70 said mold, a tubular matrix on the inner surface of the mold with the designs thereon toward the interior, a smooth paper tube on the core when expanded, and a pipe arrangement for introducing 75 molten metal into said space from the bottom upward.

6. A mold for producing cast, peripherally closed, relief engraved printing cylinders of various thickness for continuous rotary printing comprising a removable tubular outer mold, a variably expandable inner core, and means between said mold and core for producing a peripherally closed, cast, 80 relief engraved printing cylinder.

Signed at New York, N. Y., this 31 day of July, 1916.

EMIL T. NEBEN.
